JOHN J. HERLIHY, OF GLENWOOD, PITTSBURGH, PENNSYLVANIA

DESIGN FOR A RADIOCABINET

Application filed May 7, 1930. Serial No. 35,518. Term of patent 14 years.

To all whom it may concern:

Be it known that I, JOHN J. HERLIHY, a citizen of the United States, residing at Glenwood, Pittsburgh, in the county of Allegheny and State of Pennsylvania, have invented a new, original, and ornamental Design for Radiocabinet, of which the following is a specification, reference being had to the accompanying drawings, forming part thereof.

Figure 1 is a front elevation of a radio cabinet, showing my new design.

Figure 2 is a top plan view of the same.

I claim:

The ornamental design for a radio cabinet, substantially as shown.

JOHN J. HERLIHY.
